UNITED STATES PATENT OFFICE

153,620

DESIGN FOR A PLEATED FABRIC

Robert J. Nelson, New York, N. Y.

Application August 25, 1947, Serial No. 141,066

Term of patent 14 years

(Cl. D92—1)

To all whom it may concern:

Be it known that I, Robert J. Nelson, a citizen of the United States of America and resident of New York, county and State of New York, have invented a new, original, and ornamental Design for a Pleated Fabric, of which the following is a specification, reference being had to the accompanying drawings, forming part thereof.

Fig. 1 is a plan view of a piece of pleated fabric embodying my new design;

Fig. 2 is a cross-sectional view taken along line 2—2 of Fig. 1; and

Fig. 3 is a cross-sectional view taken along line 3—3 of Fig. 1.

I claim:

The ornamental design for a pleated fabric, as shown.

ROBERT J. NELSON.
